MASSACHUSETTS.

DISTRIBUTION SYSTEM FOR VAPOR ELECTRIC APPARATUS.

1,272,463.

Specification of Letters Patent.

Patented July 16, 1918.

Application filed August 27, 1909. Serial No. 514,907.

To all whom it may concern:

Be it known that we, CHARLES A. KRAUS and ROY D. MAILEY, citizens of the United States, and residents of Newton Highlands 5 and Lynn, in the counties of Middlesex and Essex and State of Massachusetts, have invented new and useful Improvements in Distribution Systems for Vapor Electric Apparatus, of which the following is a specification.

Our invention relates to the arrangement and operation of vapor electric apparatus, of which the well-known vapor rectifier is an example, and consists in a system of electrical distribution whereby the operation of such apparatus is safeguarded against the usual consequences of short circuiting, and whereby also alternating currents of greater magnitude than have heretofore been employed 10 may be successfully manipulated.

Generally speaking, the mode by which we attain the objects of our invention is to employ a pair of rectifier containers in each of which provision is made for maintenance 15 of the arc by a pair of anodes, one of which however lies in a circuit equipped with controlling reactance so that the function of this anode is to maintain the arc, while the other anode is in the working or load circuit. The relationship of the working anodes of the two containers is such that each provides an electrical check valve while their location in different containers makes it impossible for short circuiting to take place 20 between them. Thus the arc maintaining advantages of the two-anode containers are combined with the advantages of immunity from short circuiting. Moreover, both the arc-maintaining and load circuits are excited 25 from a source of alternating current so that the complication of independent circuits for arc maintenance, which has been resorted to to a limited extent, is eliminated from the construction and operation of our apparatus.

In the rectifiers in common commercial use 30 at the present time two anodes and a mercury cathode are contained in a single envelop, the current flowing alternately in one anode and the other and always through the load. It is evident that in such an arrangement when the current on one anode is a maximum the potential which the check valve action of the other anode must restrain is also a maximum. In other words, 35 the tendency to force the current through the

anode and form a short circuit, is greatest on the anode which should be inactive.

We have found by experiment that the reliability of the check valve action of the anodes is largely qualified by the current 40 flowing on the anode at the time that the given anode is exerting its check valve action. The ideal condition would be one in which no current whatever were flowing in the container at the time that the anode 45 acts as a check valve. However, since it is necessary to keep the arc alive in order that the desired current may flow in the next half cycle, it is indispensable to maintain an actuating or auxiliary current, and advan- 50 tageous to keep that current as small as possible. A small auxiliary current is adequate to keep the arc alive since if a current flows in the container the entire space within is a good conductor. Under such conditions, the 55 resistance which an anode offers to allowing a current to pass into it breaks down very readily.

We have, therefore, devised a system wherein the two half cycles which are to 60 furnish current for the load, are rectified in two structurally independent but functionally coöperating vacuum containers each equipped with a mercury cathode and an anode through which the main current flows. 65 This anode we will term the "main anode." Since it is necessary to provide also for maintaining the arc during the half cycle when no current flows in the main anode, an auxiliary anode is provided in each container, and supplied with alternating current of the proper phase relations. The current need not exceed three or four amperes. In a 500 ampere rectifier the current in the 70 container at the time that the anode is checking the main current, is less than 1/100 of 75 that which it would be under the conditions of operation customarily employed.

We are aware that rectifiers containing a single main anode have been suggested and 80 possibly a primitive type of such rectifier may have been operated. The rectifier grew out of the mercury arc lamp when it was attempted to employ alternating current with such lamps. Accordingly, an auxiliary electrode was introduced for the purpose of maintaining the arc. Apparently, 85 however, those engaged in the development of the rectifier overlooked entirely the advantages of this system, which we shall call 90

the "divided rectifier" system. No serious attempt seems to have been made to develop this system. On the other hand, the development of the art has resulted in the combination of both anodes in a single envelop. This method has been applied successfully to rectifiers of small capacity, but when large currents were attempted, short circuit arcs resulted.

10 From our studies of the check valve efficiency of an anode in a mercury vapor which was rendered conducting by the presence of an arc, we were led to believe that for large currents, the divided rectifier system is the 15 only one that can be successfully applied. We have constructed rectifiers of this type carrying upward of 500 amperes without any arcing whatsoever.

10 The vacuum envelops in these rectifiers 20 were constructed of metal. In the case of metal rectifiers, the divided type of apparatus is of especial advantage, since it makes it possible to employ symmetrical cylindrical containers which make this construction very 25 simple.

In the drawing hereto annexed there is shown diagrammatically a duplex rectifier system which embodies our invention.

10 In this drawing the conventional representation of the rectifier containers is that which is ordinarily used to denote the glass containers of commercial practice. Our invention however, contemplates the employment of currents of such magnitude as to 35 render the employment of metal containers practically necessary.

10 In the accompanying drawing V and W represent the two rectifying units, equipped respectively with the cathodes VC and WC, 40 main anodes VA' and WA, and auxiliary anodes VA and WA'. WP and VP' are transformer primaries connected to the alternating current line wires. VS' and WS are the secondaries whose mid point is connected to one end of the load circuit L, the other end of the work circuit is attached to both the main anodes VA' and WA. The outer terminals of the secondaries VS' and WS are connected respectively to the 45 cathodes VC and WC. The auxiliary anodes VA and WA' are supplied with cur-

rent by the auxiliary transformers (of relatively low potential), VP and WP' being primaries and VS and WS' secondaries respectively. The auxiliary secondaries are 55 connected to the cathode together with the main secondaries, at VK and WK; VI and WI are reactances to control the auxiliary currents. The phase relations of the circuit are so adjusted, that current flows in 60 the main anodes VA' and WA in alternate half cycles. Also in each main anode and its corresponding auxiliary anode, current flows in alternate half cycles.

Should the rectifier, either V or W, arc 65 across between its anodes the presence of the control reactance (VI, or WI,) in the circuit closed by arcing will repress and control the current, preventing it from rising to dangerous values and thus preserving the rectifier itself against injury.

What we claim and desire to secure by Letters Patent is:

1. In a distribution system, a pair of 75 vacuum containers, each comprising a vaporizable cathode and two anodes, an alternating circuit peculiar to each anode of each container, certain of said circuits being of different current carrying capacity from the others, a load common to the anode circuits 80 of higher current capacity and a source of alternating current common to anode circuits of both containers.

2. In a distribution system, a pair of 85 vacuum containers, each container included in an alternating current circuit which is divided into two branches, in each of which branches is one anode and both of which branches have a cathode connection in common and a control reactance between an 90 anode and the common circuit connection, a load common to the anode circuits unaffected by control reactance and a source of alternating current common to anode circuits of both containers. 95

Signed by us at Boston, Massachusetts, this 23d day of August, 1909.

CHARLES A. KRAUS.
ROY D. MAILEY.
